METHOD OF DYEING FABRIC

Sumner H. Williams, Charlotte, N. C., assignor
to General Dyestuff Corporation, Charlotte,
N. C., a corporation of New York

Application November 24, 1939, Serial No. 305,826

1 Claim. (Cl. 8—159)

This invention relates to that method of dyeing fabric which involves subjecting the fabric, after it has been treated to the dye liquor, to the action of a developer solution to set the color.

5 Some of the objects of the invention are to provide an improved method by which a more even color in the dyed fabric may be obtained and by which the desired color may be secured with the use of a reduced quantity of dye liquor.

10 One common way of dyeing fabric with dye of that character that requires the action of a developer to set the color, is first to impregnate or treat the fabric with the dye liquor, which may be done by passing the fabric through a bath of the dye liquor or passing it between a pair of rolls, one of which operates in a bath of dye liquor, and then to subject the fabric while still wet with the dye liquor to the action of the developer. This may be done by passing the fabric

15 while still wet with the dye liquor through a bath of the developer solution or by passing the wet fabric between a pair of rolls, one of which operates in a bath of the developer solution.

One disadvantage inherent in the above operation is that if the fabric is still wet with the dye liquor at the time that it is subjected to the action of the developer, some of the dye ingredients are likely to be washed out of the fabric by the developer, thereby reducing the amount of 20 dye remaining in the fabric. As a result, the finished fabric is likely to have a different shade or color from that which was intended, thus making it difficult to dye fabric to match any given shade or color.

25 Furthermore, because of the loss of the dye ingredient which is thus washed out of the fabric by the developer, it becomes necessary to use an excessive amount of dye to produce color of a desired depth or intensity.

30 Moreover, such loss of the dye ingredient from the fabric is apt to occur unevenly through the area of the fabric with the result that more dye will be retained in certain portions of the fabric than in other portions thereof, thereby producing 35 an unevenly dyed fabric.

It has also been suggested to dry the fabric after it has been treated to the dye liquor and before it is subjected to the action of the developer, but it has been found that with ordinary 40 drying methods, there is apt to be more or less migration of color in the fabric during the drying operation due to the fact that the drying does not occur evenly throughout the fabric, that is across the fabric from one edge to the other, or 45 from one face to the other. This is especially

true in the case of cotton fabrics that are being dyed with a color which has little or no affinity to the cotton fibre.

When a fabric is dried unevenly, as for instance, when the marginal portions of a web of 5 fabric are dried before the center portion of the web, there will exist a tendency for the dye liquor and consequently the color to migrate by capillary attraction from the wetter portions of the fabric to the dryer portions, and if the color is 10 evenly distributed throughout the fabric as it comes from the dye liquor, and migration of color such as above referred to will produce an uneven distribution of color in the fabric, the portions 15 of the fabric in which the drying proceeded most rapidly having an excess of color while the slower-drying portions of the fabric have a deficiency of color.

The present invention has for its principal 20 object to provide improvements in the above-mentioned method of dyeing fabric in which the fabric is subjected to a drying operation after it has been treated with the dye liquor but before it is subjected to the action of the developer, by 25 means of which improvements the steps of impregnating the fabric with the dyestuff, drying the dyed fabric, and then subjecting the dried dyed fabric to the action of the developer, are carried out as a continuous process, the web of 30 fabric to be dyed being given a travelling movement which takes it first through the dye bath, thence through the dryer, and thence through the developer bath. Furthermore, by means of 35 my present improvements, the step of drying the fabric prior to its treatment with the developer is carried out without any appreciable migration 40 of color in the fabric, with the result that when the dried fabric is submitted to the action of the developer, the dye ingredient has the same even distribution throughout the fabric as it had before the drying operation took place. By thus 45 eliminating any appreciable migration of color in the fabric after it has been treated to the dye liquor, but before it is subjected to the action of the developer, an evenly dyed fabric can be produced.

The fact that the fabric is dry when it is passed 50 through the bath of developer solution has the advantage that the application of the developer to the fabric does not wash the dye ingredient out of the fabric as frequently happens when the fabric is passed through the developer bath while it is still wet with the dye liquor. There is, therefore, no loss of dye ingredient during the 55 developing stage, and hence any desired shade or

color in the fabric can be produced with the expenditure of a less quantity of the dye ingredient than when a considerable portion of the dye ingredient is washed out of the fabric by the developer solution. My improved method of dyeing is of especial advantage for dyeing cotton fabrics with Algosol or Naphthol colors or other colors which have little or no affinity for cotton fibre. In drying the dyed fabric, I propose to use a vapor dryer which is constructed so as to produce the even drying of the web of fabric from one edge to the other as the fabric passes progressively through said dryer, and in this way, the dyestuff which may have little or no affinity for the cotton fibre becomes fixed thereto sufficiently so that it will not be loosened from the fibre when subjected to the developing bath.

In order to give an understanding of the invention, I have illustrated diagrammatically in the drawing an apparatus by which my improved method may be carried out.

In the drawing:

Fig. 1 is a diagrammatic layout showing an apparatus for carrying out the improved method;

Fig. 2 is a fragmentary sectional view on an enlarged scale, on the line 2—2, Fig. 1;

Fig. 3 is a fragmentary sectional view on the line 3—3, Fig. 2.

In the drawing, 1 indicates the fabric which is being dyed, and 2 indicates generally a device for applying the dye liquor to the fabric. This device may have any suitable or usual construction, and as herein illustrated, it comprises two rolls 3 and 4 between which the fabric passes, the roll 4 operating in a bath 5 of dye liquor so that the rotation of the roll 4 as the fabric passes between the rolls will apply the dye liquor to the fabric in the proper quantity.

6 indicates an apparatus for applying the developer solution to the dyed fabric in order to set the color, and while this apparatus may also have various constructions without departing from the invention, yet I have shown it as comprising two rolls 7 and 8 between which the fabric passes, the roll 8 operating in a bath 9 of the developer solution, and thus, by its rotation, applying the developer solution to the fabric.

In accordance with the present invention, the fabric 1 is subjected to a drying operation immediately after the dye has been applied thereto and immediately before it is treated with the developer solution, the said dyeing, drying and developing steps being carried out as a continuous operation, so that the web of fabric is subjected progressively to the three successive steps of the complete operation, and said drying operation is carried out in such a way that there will be no appreciable migration of color in the fabric while the moisture is being removed therefrom. Such migration of color occurs when the fabric is dried unevenly, as for instance, if during the drying operation the edges of the fabric are dried faster than the center portion thereof, or if the center portion is dried faster than the marginal portions. Under such circumstances, where an area of the fabric which is still relatively wet lies adjacent an area of the fabric which is considerably dryer, the moisture in the wetter area of the fabric will travel or migrate by capillary attraction into the dryer portion of the fabric, and such migration of the moisture will carry with it some of the dye ingredient in the fabric, thereby producing a deficiency of color in the wetter areas and a surplus of color in the dryer areas.

This migration of color is particularly noticeable in dyeing cotton fabrics with Algosol or Naphthol colors or other colors which have little or no affinity for cotton fibre, and it occurs when the moisture content of the wetter area of the fabric is considerably greater than that of the adjacent dryer area, and the extent or rate of the migration decreases as the difference in the moisture content of the fabric between the wetter and the dryer portions decreases. Hence if the drying of the fabric is so carried out that at any given point in the length of the fabric the center portion and the marginal portions of the web are dried at approximately the same rate so that there is no appreciable difference at any time during the drying operation between the moisture content of the fabric at the center portion and at the marginal portions, then there will be no appreciable migration of color during the drying operation.

If, therefore, it be assumed that there is an even distribution of the dye ingredient in the fabric after the dye liquor has been applied thereto, then if the drying of the fabric is carried out as above set forth and without any appreciable migration of color in the fabric, this same even distribution of the dye ingredient will exist in the fabric after it has been subjected to the drying operation, and when it is subsequently subjected to the action of the developer solution.

It is desirable that the fabric should be evenly saturated with the dye solution 5 before it is subjected to the drying operation, and to provide for this, the fabric is shown as passing over a series of so-called "sky-rolls" 11 which are located between the dye-applying apparatus 2 and the dryer. The passage of the cloth over the sky rolls provides a suitable time interval during which the dye liquor which has been applied to the cloth by the roll 4 may penetrate the cloth completely so as to be evenly distributed therein.

The dryer by which the fabric is dried evenly and without any migration of color is indicated generally at 10, and I propose to employ a drying apparatus constructed somewhat on the order of the apparatus illustrated in U. S. Patent 2,071,015, February 16, 1937. This dryer is a recirculating vapor dryer and comprises an elongated drying space 15 through which the cloth passes and which is bounded by two opposite walls 16, 17, each of which is provided with nozzles 18 in the form of transverse slits through which the drying medium is directed against the fabric 1 in sheet-like jets of high velocity. This drying space 15 and its bounding walls 16 and 17 are located within a housing 19 of the dryer 10, and said drying space 15 is shown as having a zigzag shape, the fabric being guided in its passage through the zigzag space 15 by suitable rolls 20.

The drying medium is delivered to the nozzles 18 under the required pressure by means of two fans or blowers 21, 22, situated at opposite ends of the housing and which produce a recirculation of the drying medium within the housing. The blower 21 delivers the drying medium into an air passage 24 beneath the zigzag drying space 15 and the blower 22 delivers drying medium into an air passage 26 above said zigzag drying space 15. The drying space 15 extends the width of the fabric and both sides thereof are open to channels or air passages 31 at the sides of the housing 19 and which extend to the inlet of the blowers or fans 21, 22.

The dryer 10 is equipped with suitable heaters 23 for maintaining the drying medium at the

proper temperature and is also preferably equipped with some suitable heat-controlling device (not shown) by which the drying medium is automatically kept at the required temperature.

5 In operation, the fan or blower 21 delivers heated drying medium under pressure into the air passage 24, and such drying medium is delivered through the nozzles or slots 18 in the wall 17 in the form of sheet-like jets of high velocity 10 which are directed against the fabric 1. Upon striking the fabric, each sheet-like jet becomes divided into two streams which flow in opposite directions along the surface of the fabric at high velocity for short distances and which develop 15 into whirling cyclonic currents, indicated at 32 in Fig. 3, said cyclonic currents being discharged through the open sides of the drying space 15 into the channels 31 which lead back to the inlet of the blower 21. The blower or fan 22 acts in 20 a similar way to deliver drying medium under considerable pressure into the air passage 26, from which the drying medium is delivered in high velocity sheet-like jets through the nozzles 18 of the wall 16, which jets are directed toward 25 and impinge against the fabric 1. The high velocity sheet-like jets thus issuing from the nozzles 18 in the wall 16 become divided into cyclonic currents upon striking the fabric, which flow laterally into the channels 31 at the sides of the 30 housing through which the heated drying medium is returned again to the blower 22.

Since the drying is done by recirculating the drying medium, it will be necessary to provide the housing with a discharge outlet through 35 which moisture laden drying medium is discharged, and also to provide the housing with an air inlet through which fresh air may be admitted. Such outlet and inlet are commonly employed in dryers in which the drying medium is recirculated, and hence it is not deemed necessary to illustrate them herein.

As an aid in obtaining the necessary even drying of the fabric so as to prevent any migration of color during the drying operation, I propose 40 to employ adjustable baffle members 27 situated in the air passages 24 and 26 and designed to direct the flowing drying medium into the narrow spaces 28 so as to maintain as far as possible the proper pressure in each of the narrow spaces 45 28 to produce a jet of the required velocity from each of the nozzles.

I find excellent results are secured by maintaining the drying medium in the dryer 10 at a temperature of between 220° F. and 320° F., depending somewhat on the character of the fabric being dried, suitable means, not shown, being employed for maintaining a uniform temperature.

The recirculating drying medium at the above 50 temperature carries a considerable amount of superheated water vapor, which, when dyeing cotton fabric, is especially effective in securing fixation of colors that have little or no affinity for cotton fibre. The use of the superheated 55 water vapor as drying medium, together with the manner in which each high velocity jet of such drying medium is directed against the cloth and is thereby converted into the whirling cyclonic currents, produces a substantially even 60 drying of the fabric from edge to edge and from back to face, thereby eliminating the undesirable migration of color which causes an unevenly dyed 65 fabric.

In carrying out the invention it is not necessary to remove all the moisture from the cloth in the dryer 10, as the object of the invention will be accomplished if 85% or 90% of the moisture is removed before the fabric is subjected 5 to the action of the developer, for by the time the fabric has been dried to a point where it retains only 10% or 15% of moisture, there will be no appreciable migration of color in the fabric.

Inasmuch as the fabric is delivered from the 10 dryer 10 at a relatively high temperature, I propose to pass the fabric through a cooling device indicated generally at 12 before the fabric is delivered to the developer-applying apparatus 6. This cooling device is shown in the form of a 15 plurality of rolls 33 over which the fabric is fastened, the time interval which it takes for any portion of the fabric to travel through the cooling device 12 being sufficient to allow the fabric 20 to be cooled to the desired point.

After the fabric is delivered from the developer-applying apparatus, it may, if desired be passed over another series of sky rolls 13 for the purpose of allowing sufficient time for the developer 25 to penetrate through the cloth and properly perform its function to set the color.

From the sky rolls 13 the dyed fabric will be taken to any suitable washing device where it is washed, and may then be finally dried by any 30 suitable means.

It is to be noted that the steps of applying the dye liquor to the fabric, drying the fabric evenly so as to avoid any migration of color in the fabric during the drying operation, and then subjecting the fabric to the action of the developer, 35 are carried out as one continuous operation, the step of drying the fabric so as to avoid any migration of color following immediately after the dyeing of the fabric, and the step of subjecting the dried fabric to the action of the developer 40 following immediately after the fabric is dried.

By drying the fabric by the use of the high-velocity sheet-like jets of drying medium which, upon striking the fabric, are converted into cyclonic currents, as indicated in Fig. 3, which not 45 only have the cyclonic form, but also flow laterally into the side spaces 31, and maintaining the drying medium at the proper high temperature, the drying operation may be carried out evenly from edge to edge of the fabric so that there will 50 be no wetter portions either at the center of the fabric or at the edges lying adjacent dryer portions which would result in the undesirable migration of color.

This application is a continuation in part of 55 my application, Serial No. 187,412, filed January 28, 1938.

I claim:

The method of continuously dyeing fabric which consists in impregnating the fabric with 60 dye liquor of the type which requires the action of a developer to set the color, and immediately thereafter such impregnation and as a step continuous therewith, drying the dye-impregnated fabric with a gaseous medium evenly and at the same 65 rate from edge to edge of the fabric and without any appreciable migration of color in the fabric during the drying operation, and then immediately subjecting the dried dyed fabric to the action of a suitable developer to set the color. 70

SUMNER H. WILLIAMS.
